UNITED STATES PATENT OFFICE.

ABBOTT THAYER MAYNARD, OF ALLSTON, MASSACHUSETTS.

DESIGN FOR A BRUSH-BROOM.

SPECIFICATION forming part of Design No. 24,185, dated April 9, 1895.

Application filed March 13, 1895. Serial No. 541,628. Term of patent 7 years.

To all whom it may concern:

Be it known that I, ABBOTT THAYER MAYNARD, a citizen of the United States, residing at Allston, in the county of Suffolk and State of Massachusetts, have invented and produced a new and original Design for a Brush-Broom; and I do hereby declare the following to be a full, clear, and exact description of the same, reference being had to the accompanying drawing, forming a part thereof.

The invention relates to a new and original design for brush-brooms, and it consists in the fanciful configuration of the holding portion as shown in the accompanying drawing, wherein the design is shown in side elevation, the opposite sides being alike.

A designates the brush, B the holder, and C the handle.

The holder is decorated with the fanciful scrolls *b* and the handle has the fanciful scroll decorations *c* interspersed with representa-

tions of leaves and flowers. The central field of the holder is open and the open space is crossed by a net-work of fanciful designs as at *c'*, the strands extending diagonally across, and at right angles to each other. Below the net-work is a base *c*² which may be of any desired color.

The essential feature of the design is the holder having the fanciful net-work section or field.

Having thus described the invention, what is claimed as new, and desired to be secured by Letters Patent, is—

The design for a brush-broom, substantially as shown and described.

In testimony whereof I affix my signature in presence of two witnesses.

ABBOTT THAYER MAYNARD.
